UNITED STATES PATENT OFFICE.

AUGUSTUS UMHOLTZ, OF TREMONT, PENNSYLVANIA.

IMPROVEMENT IN LAMP-EXTINGUISHERS.

Specification forming part of Letters Patent No. **159,621**, dated February 9, 1875; application filed January 16, 1875.

To all whom it may concern:

Be it known that I, AUGUSTUS UMHOLTZ, of Tremont, in the county of Schuylkill and State of Pennsylvania, have invented a new and useful Improvement in Lamp-Extinguisher, of which the following is a specification:

Figure 1 is a perspective view of my improved lamp-extinguisher, shown as applied to a lamp-burner. Fig. 2 is a detail view of the extinguisher, and the wick-stem with which it is connected.

Similar letters of reference indicate corresponding parts.

The invention consists in attaching an extinguisher to the stem or rod by which the wick is raised and lowered, so that both may be operated together.

The invention also relates to constructing the extinguisher-plate with slots in the flanged top portion, contiguous to the top of the wick-tube, for admitting the passage of air upward to the flame or radiation of light downward, as hereinafter described.

A represents the wick-tube of an ordinary lamp-burner, B, in which the wick is raised and lowered by spur-wheels *c* that work through slots in the side of the said wick-tube A, and are attached to a shaft or stem, D. The wick-stem D works in bearings in the burner B, and has a button or milled wheel, E, attached to its end for convenience in operating it. F is the operating-plate of the extinguisher, which is placed at the upper end of the wick-tube A, and to one of its ends is attached or upon it is formed an arm, G, that passes down through a slot in the perforated plate of the burner B, and its lower end is coiled around the wick-stem D, where it is kept in place by a sleeve-collar or shoulder placed or formed upon the said stem D. The part of the stem D, around which the end of the arm G is wrapped, is made polygonal in form, or is otherwise roughened to produce enough friction to move the arm G and plate

F when said arm and plate may be unobstructed. The arm G may be connected with the stem D in various other ways, so as to be operated by friction.

The way herein shown and described has been selected as being simple and effective; but I do not wish to limit myself to that precise way. In the forward part of the plate F are formed openings *f*¹, which, when the extinguisher is drawn back, allow the air to pass up to the flame freely. Upon the rear edge of the plate F are formed small downwardly-projecting teeth or claws, *f*², to strike against the top edge of the wick-tube A, and prevent the said plate F from being carried too far forward. The backward movement of the extinguisher is limited by the arm G striking against the rear end of the slot in the perforated plate of the burner B. With this construction, when the wick is raised, the forward edge of the plate F rests against the side of the wick. When the wick is lowered by turning the stem D, as the burning end of the said wick passes into the end of the wick-tube A, the plate F is carried forward by friction, cuts off the cinder from the end of the wick, and extinguishes the flame. When the stem is turned to raise the wick the first effect is to carry back the extinguisher and then to raise the wick.

Having thus described my invention, I claim as new and desire to secure by Letters Patent—

1. The combination, with the wick-stem D, of the extinguisher F, the same being connected by arm G, as shown and described, to admit of simultaneous operation.

2. The extinguisher F G, provided with openings or slots *f*¹ in the flanged top portion, as and for the purpose specified.

AUGUSTUS UMHOLTZ.
